No. 728,771.

PATENTED MAY 19, 1903.

J. B. SCHUMAN,
GRAIN ELEVATOR.
APPLICATION FILED AUG. 20, 1902.

NO MODEL.

UNITED STATES PATENT OFFICE.

JAMES B. SCHUMAN, OF INDIANAPOLIS, INDIANA.

GRAIN-ELEVATOR.

SPECIFICATION forming part of Letters Patent No. 728,771, dated May 19, 1903.

Application filed August 20, 1902. Serial No. 120,826. (No model.)

To all whom it may concern:

Be it known that I, JAMES B. SCHUMAN, a citizen of the United States, residing at Indianapolis, in the county of Marion and State 5 of Indiana, have invented certain new and useful improvements in Grain-Elevators; and I do hereby declare the following to be a full, clear, and exact description of the invention, such as will enable others skilled in the art to 10 to which it appertains to make and use the same.

My invention relates to certain new and useful improvements in grain-elevators, and is adapted more particularly for use upon threshing-machines and other forms of grain-separators.

My object is to provide a device that will deliver the grain from the top of the machine into any suitable receptacle—such as sacks, a wagon-bed, or the like.

20 A further and special object of my device is to so locate certain coöperating parts with respect to the top of the machine that the grain may be readily delivered at will at a desired distance from the machine on either 25 side thereof.

Other objects and advantages will be hereinafter more fully set forth in the following specification.

In the drawings, Figure 1 is a side elevation of a portion of a threshing-separator with my improvement attached thereto. Fig. 2 is a detail top plan view of the blast-fan or throwing-wheel and accessory parts. Fig. 3 is a central vertical sectional view thereof, 35 and Fig. 4 is a sectional view through the bearing as seen from the dotted line *x* *x* in Fig. 3.

Similar reference-numerals designate corresponding parts throughout the drawings, of 40 which—

1 indicates a separator, which may be of any preferred form or construction. Mounted upon one side of the separator in any preferred way, one end of which registers with 45 the usual discharge-spout common to all separators, is an elevator 2, having at its upper end a delivery-spout 3, through which the grain is delivered into any preferred weigher 4 or hopper. The grain is carried from the discharge-spout (not shown) of the separator up 50 to the delivery-spout 3 by means of buckets

5 or any form of elevator, it being immaterial what class of elevator is used.

It has heretofore been difficult to deliver grain at any desired point on either side, 55 above, or in front or in the rear of the machine or into a wagon or other receptacle so located without carrying it to a great height above the machine and the use of heavy and costly machinery. To obviate all these serious objections and at the same time to deliver the threshed grain or other product at any desired point on either side, above, or in front or in the rear of the machine or into a wagon or receptacle so located, I mount the 65 fan-housing 6 in a horizontal position upon and in respect to the top of the machine 1, the said housing having a downwardly-extending tubular shaft 7, the said shaft being adapted to fit down into and be supported by a 70 tubular socket 8, the said socket being secured to the separator in any preferred manner, as by brackets 9. The upper side of the housing 6 is provided with a hopper 10, into which the grain is discharged from the weigher 4. 75 The housing 6 is also provided with a suitable discharge-pipe 11, said pipe being preferably cylindrical in form, having a suitable delivery-spout 12 at its outer end, and being attached directly to the housing 6 by a flexible joint 13. The pipe 11 is preferably made in two or more sections telescopically attached together and is designed to be raised or lowered and also supported through the medium of the cable 14, as shown, the said cable being controlled by a swivelly-mounted winding-drum 15.

Entering through an orifice in the lower end of the tubular socket 8 and through the tubular shaft 7 is a driving-shaft 16, the said 80 shaft carrying at its upper end a series of throwing-blades 17, the lower end thereof being mounted in a suitable bearing 18, which is in turn secured to the side of the machine 1. Power is transmitted to the shaft 16 in 85 any preferred way, as by bevel-gears 19 and 20, respectively.

It will be seen that by having the housing 6 revolvably mounted in the socket 8 it may be turned so as to deliver the grain into any 90 suitable receptacle at any desired point on either side, above, in front, or in the rear of

the machine, as clearly demonstrated by means of the full and dotted lines in Fig. 2 of the drawings.

I also desire it to be understood that the 5 bearings supporting the housing 6 may be replaced by ball-bearings, if deemed desirable.

In operation the grain is elevated by the buckets 5 or other means and discharged into the weigher 4. The grain is then automatically weighed and dumped into the hopper 10, whence it enters into the housing 6 and is thrown out through spouts 11 and 12 and into a suitable receptacle by the throwing-blades 17. By so constructing and placing the housing 6 I am enabled to build the same of very light material and at the same time retain its durability and efficiency.

Should it not be desired to weigh the grain, the weigher 4 is dispensed with and the grain 20 then discharged directly into the hopper 10.

While I have described the preferred combination and construction of the parts deemed necessary to materialize my invention, I wish to comprehend all equivalents and substitutes 25 as may be considered as falling fairly within the scope of my invention.

Having thus fully described my invention, what I claim as new, and desire to secure by Letters Patent, is—

30 1. A grain-separator or the like having a grain-delivery chute at the top of the machine, in combination with a grain-throwing wheel having a horizontally-disposed casing located at the top of the machine and adapted to receive the grain from said chute, and a conveyer-chute coöperating with said casing adapted to swing in any desired direction whereby the grain will be delivered at the point desired all substantially as specified and 40 for the purpose set forth.

2. The combination with a grain-separator having a grain-delivering chute terminating at the top of the machine, of a grain-throwing wheel located below the discharging end of 45 said chute and having a casing rotatably dis-

posed in a horizontal plane and also having a receiving-hopper and a flexible discharge-tube adapted to deliver the grain at any desired point, as set forth.

3. The combination with a grain-separator 50 having a grain-delivering elevator extending to the top of the machine of a grain-throwing wheel having a horizontally-disposed casing, said casing being provided with a depending journal, and suitable bearings for said journal, whereby the casing may freely turn in either direction and means to deliver the grain from the casing as set forth.

4. In a grain separator and elevator, the combination with the grain-discharge chute of 60 a grain-throwing wheel provided with a casing and delivery-nozzle, said casing being rotatably disposed in a horizontal plane on top of the machine and suitable means to hold it in any desired position whereby the grain 65 may be delivered upon either side of the machine as set forth.

5. In a grain-separator, a grain-throwing wheel having a casing disposed in a horizontal plane on top of the machine and provided 70 with a depending sleeve or tubular journal in combination with a suitable supporting-bearing for said sleeve, whereby the casing may be turned in either direction as desired.

6. In a grain separator and elevator, the 75 combination with a delivery-chute of a grain-throwing wheel having a horizontally-disposed casing and a centrally-disposed depending journal, suitable receiving and supporting bearings for said journal carried by 80 the machine, and an automatic grain-weigher interposed between the grain-throwing wheel and the delivery-chute of the machine, all combined substantially as specified.

In testimony whereof I affix my signature 85 in presence of two witnesses.

JAMES B. SCHUMAN.
